UNITED STATES PATENT OFFICE.

FRANK M. DRAKE, OF NASHVILLE, TENNESSEE, ASSIGNOR TO FEDERAL CAN COMPANY,
OF NASHVILLE, TENNESSEE, A CORPORATION OF TENNESSEE.

RECEPTACLE.

Application filed April 12, 1927. Serial No. 183,028.

This invention relates to means for locking the cover of a receptacle to the body thereof and more particularly to such means as applied to receptacles of the character known to the art as cans.

An object of the present invention is to provide means whereby the cover of a receptacle may be locked to the body thereof.

Accordingly the present invention consists in a receptacle preferably of that character known to the art as a can having a cover which may be locked thereto to prevent disengagement therefrom. In the preferred form of the invention the body of the device is provided with spaced slots and that portion of the top fitting around the body is provided with integral tapered tongues which may engage the slots. In a modified embodiment of the invention, the body of the device is provided with pairs of spaced slots, that portion of the body between the slots of the respective pairs being forced outwardly a slight amount. The portion of cover fitting around the body in this instance is provided with spaced openings corresponding to the position of the extended portions of the body and tapered pins or tongues are provided for locking the cover to the body by means on the extended portion.

Other features and objects of the invention will become apparent by reference to the accompanying drawings read in the light of the following description wherein

Fig. 1 is a perspective view of one modification of the invention showing the cover in locked position;

Fig. 2 is a similar view of the same device showing the cover removed from the body;

Fig. 3 is a sectional elevation taken on the lines 3—3 of Fig. 1;

Fig. 4 is a modified form of the device showing the cover in locked position;

Fig. 5 is a view similar to Fig. 2 of the device illustrated in Fig. 4; and

Fig. 6 is a sectional elevation taken on the line 6—6 of Fig. 4.

Referring now to Figs. 1 to 3 inclusive of the drawings, the device illustrated comprises a receptacle or can composed of a body 10 and a top or cover 11. The upper edge of the body 10 is shaped to provide a curled edge 12 and the cover is also provided with a rounded enlargement or recess 13, the purpose of which will hereinafter be

explained in full. A peripheral bead 14 spaced below the upper edge of the body 10 may be utilized to limit downward movement of the cover 11 and due to its shape, namely, a slight triangular shape, the cover upon being forced thereupon will effect a tight seal. Spaced at intervals about the periphery of the upper portion of the body are a number of slots 15. That portion of the body adjacent to the slots is bent inwardly a slight amount so that tongues may readily be inserted in the slot. A number of tongues 16 formed as integral parts of the skirt of the cover 11 adapted to fit around the body 10 are spaced at intervals corresponding to that between the respective slots 15. These tongues 16 are forced inwardly a slight amount so as to readily enter the slots 15.

From the foregoing, it may be seen that the cover 11 may be pressed downwardly upon the body and then turned until the tongues enter the slots 15. Due to the tapered shape of these tongues, the turning of the cover with the resultant contact between the top edge of the tongue and the top edge of the slot will cause the cover to be forced downwardly until a good seal is made between the lower edge thereof and the peripheral bead 14. In this position, the top may be removed only by turning the cover in the reverse direction and then lifting it from contact with the side walls of the body.

It will be evident that the foregoing arrangement of slots and tongues may be reversed, i. e., the skirt of the cover may be provided with slots and tongues may be formed as integral parts of the body. In this arrangement, after the cover has been turned until the tongues are thoroughly seated and in place in the slots, the extremities of the tongues will be outside the skirt of the cover, and if so desired may be bent backward against the skirt to prevent accidental disengagement of the body and cover.

A modification shown in Figs. 4 to 6 inclusive comprises a similar body portion 10' and cover 11' with a curled edge 12' and curved enlargement or recess 13'. The body 10' is likewise provided with a peripheral bead 14' similar to bead 14. Spaced at intervals around the top of the body 10' are pairs of slots 20 in close proximity to each other. That portion of the body indicated at 21

which lies between the slots 20 of each of the pairs is forced outwardly to provide an enlargement. The skirt portion of cover 11' which fits around the body is provided with a number of openings 22 spaced at intervals corresponding to that between the outwardly extending portions 21. The openings 22 are of sufficient size to readily slip over the outwardly extending portions 21 and when so arranged pins 23 may be inserted as shown in Fig. 4. Due to the tapered shape of these pins or tongues 23, their action will be approximately the same as that of the tongues 16, namely, to force the cover downwardly until the lower edge thereof rests firmly against the flange 14'.

In packing and sealing a receptacle similar to either embodiment, if it is so desired, a strip of packing material or gasket may be placed in the recess 13 so that when the cover is forced downwardly upon the curled edge 12 a tight seal will be made.

From the foregoing, it will readily be seen that the present invention provides a new, simple and efficient arrangement for locking the cover of a receptacle to the body thereof, and it is to be understood that the invention

is to be limited only by the following claims.

I claim:

1. A receptacle having a body member and a cover member having a portion adapted to fit around said body member, one of said members being provided with spaced slots, and a plurality of tapered tongues each adapted to engage one edge of one of said slots to draw the cover downwardly upon said body, upon relative rotary movement between the members.

2. A receptacle having a body member and a cover member, said body member being provided with a peripheral bead near the upper edge thereof and being provided with spaced slots between said bead and said upper edge, said cover portions being provided with spaced tapered tongues formed as integral parts thereof, said tongues being adapted to engage said slots and to draw the skirt of said cover downwardly against said bead, upon relative rotary movement between the members.

In testimony whereof, I have signed my name to this specification.

FRANK M. DRAKE.
